(57) **CLAIM**

The ornamental design for a display screen, as shown and described.

DESCRIPTION

1. Display screen
- 1.1 : Perspective
- 1.2 : Front
- 1.3 : Back
- 1.4 : Left
- 1.5 : Right
- 1.6 : Top
- 1.7 : Bottom
- 1.8 : Enlarged
- 1.9 : Reference

The claimed design is characterized by having a stripe pattern in the center of the glass support where the media box can be installed; reproduction 1.8 is an enlarged view of a portion of reproduction 1.1, represented by the circle in dot-dashed lines, a curvy line and number 1.8; reproduction 1.9 is a reference view showing the media box installed to the claimed design; the broken lines showing the media box are provided for the purpose of illustrating environmental structure and form no part of the claimed design.

1 Claim, 9 Drawing Sheets
